2,404,325

EXTRACTOR-SWITCH MECHANISM FOR
MACHINE GUNSCarl G. Swebilius, Hamden, Conn., assignor to
The High Standard Manufacturing Company,
Hamden, Conn., a corporation of Connecticut

Application November 19, 1943, Serial No. 510,854

2 Claims. (Cl. 89—33)

1

The present invention relates to improvements in machine guns and relates more particularly to improvements in extractor-switch mechanisms therefor. The extractor-switch mechanism of the present invention is adapted for use in connection with machine guns of the so-called "Browning" type, which type of machine gun is disclosed in detail in United States Patent No. 1,628,226, dated May 10, 1927.

In machine guns of the Browning type above referred to, a pivotal cartridge-extractor is employed which serves to extract a fresh cartridge from a belt of cartridges as the breech-bolt moves rearwardly. Such cartridge-extractor is so actuated that upon the rearward stroke of the breech-bolt, a given cartridge from the belt is carried rearwardly and depressed by the said cartridge-extractor and ultimately brought into alignment with the cartridge-chamber of the barrel during the forward travel of the said breech-bolt. The latter part of the cartridge-depressing action of the cartridge-extractor just referred to is accomplished by a pivotal extractor-switch which serves to further depress the forward end of the cartridge-extractor as the breech-bolt moves forwardly. Shortly before the breech-bolt reaches its breech-closing position, the forward portion of the extractor-switch is depressed so that the said extractor-switch then serves to guard against the subsequent depression of the cartridge-extractor until such time as the breech-bolt is again moved rearwardly. As will more fully herein-after appear, the present invention relates to improvements in features directly related to such an extractor-switch.

One of the objects of the present invention is to provide a superior extractor-switch mechanism for machine guns characterized by simplicity and ability to withstand hard usage over long periods of service.

Another object of the present invention is to provide a superior extractor-switch mechanism capable of satisfactorily functioning in a machine gun when the latter is operated at speeds in excess of one thousand shots per minute.

With the above and other objects in view, as will appear to those skilled in the art from the present disclosure, this invention includes all features in the said disclosure which are novel over the prior art and which are not claimed in any separate application.

In the accompanying drawings, in which certain modes of carrying out the present invention are shown for illustrative purposes:

Fig. 1 is a broken view partly in side elevation

2

and partly in vertical longitudinal section of the rear portion of a machine gun equipped with an extractor-switch mechanism embodying the present invention, the parts being shown in the positions which they assume when the breech-bolt has almost reached its rearmost position and the barrel-extension has reached the limit of its rearward travel;

Fig. 2 is a view similar to Fig. 1 but showing the parts in the positions which they assume when the barrel-extension has reached its full forward position and the breech-bolt is approaching its full breech-closing position;

Fig. 3 is a broken view of a portion of the left side-plate of the machine gun looking toward the outer face thereof;

Fig. 4 is a view similar to Fig. 3 but looking toward the inner face of the side-plate;

Fig. 5 is a transverse sectional view taken on the line 5—5 of Fig. 4;

Fig. 6 is a similar view taken on the line 6—6 of Fig. 4;

Fig. 7 is a view in side elevation of the extractor-switch spring detached;

Fig. 8 is an edge view thereof; and

Fig. 9 is a perspective view of the extractor-switch detached.

The machine gun illustrated in the accompanying drawings is of the Browning type and includes a receiver generally designated by the reference character 10, an axially-reciprocating barrel 11, a barrel-extension 12, a breech-bolt 13 and a barrel-jacket 14.

The rear end of the barrel 11 is extended with-in the forward end of the receiver 10 for reciprocation therein, and the forward end of the aforesaid barrel-extension 12 is rigidly organized with the rear end of the said barrel for reciprocation also within the receiver 10, in a manner well known in the art. Both the breech-bolt 13 and the barrel-extension 12 (and hence also the barrel 11) may be respectively urged forwardly by suitable spring-means, not herein shown but well understood in the art and more fully shown in the Browning patent before referred to.

The breech-bolt 13 reciprocates both with and with respect to the barrel-extension 12 in a manner well known in the art. The said breech-bolt 13 is carried by the barrel-extension 12 but with capacity for reciprocation with respect thereto, as before referred to.

Pivottally connected at its rear end to the left side of the breech-bolt 13 is a cartridge-extractor generally designated by the reference character 15. At its forward end, the cartridge-extractor

15 is formed with a depending cartridge-extracting hook 16 which is adapted in a manner well known in the art to successively hook into the respective cannelures of cartridges to effect the successive individual extractions thereof from a cartridge-belt such as 17 indicated in Figs. 1 and 2.

Extending laterally outwardly from the forward end of the cartridge-extractor 15 is an integral guide-lug 18 which is adapted to coact with the edge surfaces of a lever-like extractor-switch generally designated by the reference character 19, all as will more fully hereinafter appear.

Rigidly carried by the under-face of the top-plate 20 of the receiver 10 is a downwardly-and-rearwardly sloping extractor-depressing cam 21 positioned so as to engage with the upper surface of the forward portion of the cartridge-extractor 15 to depress the same when the breech-bolt 13 moves rearwardly, as indicated in Fig. 1.

About midway of its length, the extractor-switch 19 above referred to is formed with an integral outwardly-extending and cylindrically-contoured pivot-stud or trunnion 22 which turns in a bearing-opening 23 extending laterally through the left side-plate 24 of the receiver 10. The said pivot-stud 22 is of a length materially exceeding the thickness of the side-plate 24, so as to extend outwardly well beyond the outer face of the said side-plate. Adjacent its rear end, the extractor-switch 19 is formed with an outwardly-projecting limiting-lug 25 fitting into a recess 26 formed in the inner face of the side-plate 24 before referred to. By its engagement with the upper wall of the recess 26, the said limiting-lug 25 serves to limit the upward swinging movement of the rear portion of the said extractor-switch 19.

At a point slightly outwardly with respect to the outer face of the side-plate 24, the pivot-stud 22 of the extractor-switch 19 is formed with a diametric passage or socket 27. Extending downwardly through the passage 27 just referred to is the key-portion or tension-finger 28 of an extractor-switch spring generally designated by the reference character 29. The said spring 29 may be conveniently formed of relatively-heavy spring-steel wire and includes also a loop-portion 30 and a relatively-long tension-arm 31.

In the normal unrestrained condition of the extractor-switch spring 29 above referred to, the key-portion 28 thereof is displaced outwardly with respect to the outer face of the side-plate 24, so as to exert a constant effort to yieldingly hold the outer face of the extractor-switch 19 against the inner face of the said side-plate 24. This displacement is especially clear in the showing of Fig. 8. The relatively-long tension-arm 31 of the spring 29 is hooked beneath a downwardly-facing spring-seat 32 constituting the under-face of a reinforcing-bar 33 rigidly secured to the outer face of the side-plate 24 in a location forwardly of the extractor-switch 19. When the tension-arm 31 is thus located in engagement with the spring-seat 32, the extractor-switch spring 29 acts through its key-portion 28 to yieldingly turn the extractor-switch 19 in such direction that the rear end of the said extractor-switch is raised and the forward end thereof is lowered. The turning movement just referred to is limited by the engagement of the upper face of the limiting-lug 25 of the extractor-switch 19 with the upper wall of the recess 26 in the side-plate 24, as is especially well shown in Figs. 3 and 4.

Slightly forwardly of the extractor-switch 19 is located an upwardly and-forwardly-inclined cam-bar 34 rigidly secured to the inner face of the side-plate 24 and which in a manner as will hereinafter appear, is engaged by the guide-lug 18 of the cartridge-extractor 15.

When the machine gun is discharged, the barrel 11 and the barrel-extension 12 move rearwardly, under the recoil-forces, a relatively-short distance substantially from the positions in which they are shown in Fig. 2 into substantially the positions in which they are indicated in Fig. 1. The breech-bolt 13 will coincidentally travel rearwardly with the barrel 11 and barrel-extension 12 but its stroke will be greatly in excess of the stroke of the said parts 11 and 12. The breech-bolt 13 will travel rearwardly into a position slightly to the rear of the position in which it is indicated in Fig. 1.

During the rearward travel of the breech-bolt, the cartridge-extractor 15 will, of course, travel therewith and will through the intermediary of its cartridge-extracting hook 16, withdraw a cartridge from the cartridge-belt 17 and carry such cartridge rearwardly. As the cartridge-extractor is moved rearwardly as described, the upper face of its forward portion will be in engagement with the extractor-depressing cam 21 on the under-side of the top-plate 20, with the result that the forward portion of the said cartridge-extractor together with the cartridge carried by it, will be depressed. During this rearward travel and slightly before the guide-lug 18 clears the rear end of the extractor-switch 19, the said guide-lug 18 will engage with the upper surface of the said extractor-switch 19 and depress the rear end of the latter against the tension of the extractor-switch spring 29. This condition substantially corresponds to that shown in Fig. 1.

As the breech-bolt 13 moves further rearwardly from the position in which it is shown in Fig. 1, it will carry with it the cartridge-extractor 15, and slightly before the said breech-bolt reaches the limit of its rearward travel, the forward edge of the guide-lug 18 will ride rearwardly clear of the rear end of the extractor-switch 19. As soon as this clearance occurs, the extractor-switch spring 29 will assert itself and swing the rear end of the extractor-switch 19 upwardly. Now, during the subsequent forward travel of the breech-bolt 13 and its cartridge-extractor 15, the downwardly-and-forwardly-sloping cam-surface 35 of the extractor-switch 19 will be engaged by the forward upper portion of the guide-lug 18 of the cartridge-extractor 15. The engagement just referred to will further depress the forward end of the cartridge-extractor 15 and hence also the cartridge now carried thereby until the said cartridge is horizontally in line with the cartridge-chamber of the barrel 11. The said guide-lug will now travel forwardly in a path beneath the extractor-switch 19.

Ultimately during its forward travel coincidentally with the breech-bolt 13, the guide-lug 18 of the cartridge extractor 15 will engage with the upwardly-and-forwardly-sloping cam-bar 34, but only after the cartridge which is in process of being loaded into the cartridge-chamber of the barrel 11 has been partly inserted thereinto. The resultant lifting-action of the forward end of the cartridge-extractor 15 will lift the cartridge-extracting hook 16 thereof clear of the cannelure of the cartridge now partly inserted into the cartridge-chamber of the barrel 11.

In riding-up the surface of the cam-bar 34, the

guide-lug 18 of the extractor-switch 19 will upwardly crowd the forward end of the extractor-switch 19 against the tension of the extractor-switch spring 29, as indicated in Fig. 2.

In Fig. 2 the barrel 11 and barrel-extension 12 are shown in their full forward positions and the breech-bolt 13 is shown in a position closely approaching its full forward or breech-closing position. As the cartridge-extractor 15 moves forwardly with the breech-bolt 13, from the position in which it is shown in Fig. 2 into its full breech-closing position, the rear end of the guide-lug 18 will clear the forward end of the extractor-switch 19, whereupon the forward end of the said extractor-switch will swing downwardly under the tension provided by the extractor-switch spring 29. In this manner the extractor-switch 19 will reassume its normal position, wherein the guide-lug 18 of the cartridge-extractor 15 will ride over the top of the said extractor-switch when the breech-bolt is next moved rearwardly by the subsequent discharge of the machine gun.

In former practice and as is shown in the Browning patent above referred to, it was the custom to insert a U-shaped extractor-switch spring in the recess 26 of the side-plate 24 in such manner that one arm of such spring exerted an upward tension against the underside of the limiting-lug 25. Furthermore, in the prior construction the pivot-stud such as 22 of the extractor-switch was threaded at its outer end and the entire extractor-switch was retained in place by a nut bearing against the outer face of the side-plate 24 and retained by a suitable cotter-pin. The described construction not only failed to provide a fully reliable extractor-switch spring in the cramped space available but also required that the aforesaid nut be adjusted with exactitude in order to prevent a binding action.

As will be seen from the foregoing and by reference to the accompanying drawings, the present invention provides an extractor-switch spring which not only serves the function of turning the extractor-switch but also acts as a positive key to hold the same in place in the side-plate 24. Furthermore, by suitably pre-tensioning the extractor-switch spring 29 (see Fig. 8), the said spring may be caused to yieldingly maintain the outer face of the extractor-switch firmly against the inner face of the side-plate 24.

By means of the present invention not only is the cost of the assembly reduced with respect to manufacturing operations and materials, but the assembly of the extractor-switch 19 with the side-plate 24 may be effected very rapidly and without requiring any delicate adjustments of the parts. Conversely, the disassembly of the parts for inspection or repair is similarly rendered most convenient.

The invention may be carried out in other specific ways than those herein set forth without departing from the spirit and essential characteristics of the invention, and the present em-

bodiments are, therefore, to be considered in all respects as illustrative and not restrictive, and all changes coming within the meaning and equivalency range of the appended claims are intended to be embraced therein.

I claim:

1. The combination with a machine gun having a breech-bolt and a pivotal cartridge-extractor carried by the said breech-bolt: of a hollow receiver-structure having a bearing-opening extending through a wall-portion thereof; a pivotal extractor-switch located mainly within the receiver-structure and constructed and arranged to deflect the cartridge-extractor of the machine gun, the said extractor-switch having a rigid trunnion extending outwardly through and beyond the bearing-opening in the adjacent wall-portion of the said receiver-structure, the said trunnion having a spring-receiving socket therein located in its portion projecting outwardly beyond the said wall-portion; and a laterally-bendable spring having one end held by the said receiver-structure and having its opposite end extended into the spring-receiving socket in the trunnion of the said extractor-switch to turn the said trunnion and hence also turn the said extractor-switch and to also act as a positive key to limit the inward displacement of the said trunnion, the end of the spring which is entered into the socket in the trunnion of the extractor-switch being pre-set outwardly away from the outer face of the adjacent wall-portion of the receiver-structure to thereby draw the said trunnion outwardly.
2. The combination with a machine gun having a breech-bolt and a pivotal cartridge-extractor carried by the said breech-bolt: of a hollow receiver-structure having a bearing-opening extending through a wall-portion thereof; a pivotal extractor-switch located mainly within the receiver-structure and constructed and arranged to deflect the cartridge-extractor of the machine gun, the said extractor-switch having a rigid trunnion extending outwardly through and beyond the bearing-opening in the adjacent wall-portion of the said receiver-structure, the said trunnion having a spring-receiving socket therein located in its portion projecting outwardly beyond the said wall-portion; and a torsion-type spring having an inner end extended into the spring-receiving socket in the trunnion of the said extractor-switch to turn the said trunnion and hence also turn the said extractor-switch, the said spring having a loop-portion extending from its said inner end and also having an outer end extending from the said loop-portion away from the said inner end and engaged with a portion of the said receiver-structure, the inner end of the said torsion-type spring being pretensioned outwardly to exert a constant-but-yielding effort to draw the said trunnion outwardly with respect to the said receiver-structure.

CARL G. SWEBILIUS.
